TAPE TRANSPORT

John H. Wilson, Tulsa, Okla., assignor to Telex
Computer Products, Inc., Tulsa, Okla.

Filed Jan. 17, 1972, Ser. No. 218,651

Term of patent 14 years

Int. Cl. D14—02

U.S. Cl. D26—5 C

FIG. 1 is a front elevational view showing the design.
FIG. 2 is an elevational view of one side of the design,
the opposite side being a mirror image of the side illus-
trated.

FIG. 3 is a rear elevational view of the design.

FIG. 4 is a top plan view of the design.

I claim:

The ornamental design for a tape transport, substan-
tially as shown and described.
